UNITED STATES PATENT OFFICE.

GEORGE W. DAYMON, OF PHILADELPHIA, PENNSYLVANIA.

SWEEP-STICK COUPLING.

1,241,829.

Specification of Letters Patent.

Patented Oct. 2, 1917.

Application filed December 14, 1916. Serial No. 136,914.

To all whom it may concern:

Be it known that I, GEORGE WASHINGTON DAYMON, a citizen of the United States, residing at Philadelphia, in the county of 5 Philadelphia and State of Pennsylvania, have invented new and useful Improvements in Sweep-Stick Couplings, of which the following is a specification.

My invention relates to new and useful 10 improvements in sweep stick coupling, and has for its object to provide an exceedingly simple and effective device of this character, whereby said sweep stick will be free to follow the motions of the picker stick, which 15 has a certain amount of sidewise movement during its action to and fro.

A further object of the invention is to provide a sweep stick and its coupling which will be exceedingly light in weight, 20 and to this end I make the rocker arm connection of aluminum or other suitable light weight material, said rocker arm connection being connected with the sweep stick through the medium of an aluminum or 25 stiff leather strap, the latter being so constructed that any wear between the parts may be readily taken up and the lost motion practically eliminated.

Another object of the invention is to provide 30 the rocker arm connection with oil holes, whereby the different bearing surfaces may be properly lubricated.

With these ends in view, this invention consists in the details of construction and 35 combination of elements hereinafter set forth and then specifically designated by the claims.

In order that those skilled in the art to which this invention appertains may understand 40 how to make and use the same, I will describe its construction in detail, referring by numerals to the accompanying drawing forming a part of this application, in which—

45 Figure 1, is a fragmentary end view of a loom, showing my improved sweep stick applied thereto.

Fig. 2, is an enlarged side elevation of the sweep stick and coupling.

50 Fig. 3, is a plan view thereof.

Fig. 4, is a section at the line 4—4 of Fig. 3.

Fig. 5, is a section at the line 5—5 of Fig. 2; and

55 Fig. 6, is a plan view of the sweep stick,

showing a slightly different construction of rocker arm connection.

In carrying out my invention as here embodied 60 2 represents a loom frame of any ordinary and well known construction provided with a picker stick 3 and a picking arm bracket 4, with which is connected the picking arm 5, having a stud 6. On this stud is journaled the rocker arm connection 7, preferably formed of aluminum because 65 of its lightness, and this rocker arm connection comprises a bearing sleeve 8 having a stud opening 9 therethrough, and provided with an oil hole 10 leading from the outside surface to the stud opening 9. 70

From the bearing sleeve projects a pair of approximately parallel integral arms 11 connected together at their outer ends by an integral post 12, circular in cross section as will be plainly seen in Fig. 5. Through 75 one of the arms 11 adjacent its outer end and longitudinally through the post 12 to a point intermediate its ends runs a vertical oil hole 13, the inner end communicating with a transverse oil hole 14 passing entirely through the post 12 as plainly shown in Fig. 4.

The outer ends of the arms 11 are arcuate in plan to coincide with the circular contour of the post 12, and said post and the 85 outer ends of the arms 11 register with an arcuate vertical groove 15 formed in the inner end of the sweep stick 16 when said sweep stick and the rocker arm connection are connected. To connect the sweep stick 90 and rocker arm connection, I provide a strap 17 of aluminum, stiff leather or other suitable material having adjusting slots 18 adjacent the ends, and this strap overlies two opposite side faces of the sweep stick 95 and passes around the post 12, the same being adjustably secured to the sweep stick by means of a suitable fastening member 19, such as a screw or bolt which passes through the slots 18 and through a hole 20 100 adjacent the inner end of the sweep stick, said fastening member having a nut 21 threaded on one end thereof for drawing the parts firmly together to hold said parts in their adjusted position and prevent the 105 accidental displacement of the fastening member, and if found desirable, washers 22 may be interposed between the strap 17 and the head of the fastening member and the nut. 110

The opposite or outer end of the sweep stick is provided with a hole 23, whereby the ordinary lug strap 24 may be attached thereto by a suitable fastening device, said strap connecting the sweep stick with the picker stick 3 and being held in place by the retaining strap 25.

In Fig. 6 I have shown the bearing sleeve 8 of the rocker arm connection of the same width as the arms 11, thereby eliminating the extensions of the bearing sleeve which project beyond each side of the arms 11 as shown in Fig. 3. In some cases it is necessary to have a wide or long bearing sleeve, while in others the bearing sleeve must be relatively short or narrow, depending upon the space between the parts of the bifurcated end of the picking arm, which varies considerably in different makes of looms, and I do not wish to be confined to any particular length or width of the parts, nor the particular configuration of the device which varies according to the different dimensions.

By referring to Fig. 4 it will be seen that when a suitable lubricant is placed in the oil hole 18, said lubricant will pass downward through said hole into the transverse hole 14 where it will pass to the bearing surfaces of the post 12, sweep stick 16 and strap 17, properly lubricating said surfaces, so as to reduce the wear and friction to a minimum. The bearing surfaces of the stud 6 and bearing sleeve 8 are lubricated through the oil hole 10 as will be obvious.

In practice during the running of a loom, the picker stick has a certain amount of sidewise movement during the actions of said picker stick to and fro, and the position of the outer end of the sweep stick or the end connected with the picker stick also has a certain amount of vertical movement, and the object of my invention is to provide a sweep stick coupling or the combination of a sweep stick and rocker arm connection, which will permit the sweep stick proper to follow the above described movements of the picker stick with very little lost motion, and without undue strain upon the sweep stick or its contiguous parts which under present conditions often breaks, damages or disarranges the parts.

As will be readily understood from the

drawings, the sweep stick will be permitted to move in a vertical direction about the 55 stud 6 in the arc of a circle about said stud, so as to follow the rise and fall of the retaining strap 25 on the picker stick, and since the sweep stick proper is hinged to the rocker arm connection by the strap 17, 60 said sweep stick is permitted to move horizontally or sidewise so as to follow the side-wise movement or play of the picker stick.

Of course I do not wish to be limited to the exact details of construction as herein 65 shown, as these may be varied within the limits of the appended claims without departing from the spirit of my invention.

Having thus fully described my invention, what I claim as new and useful, is— 70

1. In a device of the character stated, a rocker arm connection comprising a bearing sleeve having a stud opening therethrough and provided with an oil hole integral arms projecting from said bearing sleeve, a post formed integral with the outer ends of said arms, said post being circular in cross section, one of said arms and said post having an oil hole extending therethrough to a point intermediate to the ends of 80 the post, said post having another oil hole passing transversely entirely therethrough and communicating with the first named oil hole, a sweep stick provided with an arcuate groove registering with the post of the 85 rocker arm connection, and a strap passing around said post and adjustably connected to the sweep stick for hingedly fastening said sweep stick to the rocker arm connection. 90

2. In a device of the character stated a rocker arm connection comprising a bearing sleeve having a stud opening therethrough, integral arms projecting from said bearing sleeve, and a post formed integral with the outer ends of said arms, said post being circular in cross section, in combination with a sweep stick having an arcuate groove at one end to register with said post, and a strap passing around said post and adjustably connected to the sweep stick for hingedly fastening said sweep stick to the rocker arm. 95

In testimony whereof, I have hereunto affixed my signature.

GEORGE W. DAYMON.
